ADJUSTABLE RAZOR HEAD

Russell E. Benner, New York, N. Y., assignor, by
mesne assignments, to Remington Rand Inc.,
Buffalo, N. Y., a corporation of Delaware

Application October 29, 1937, Serial No. 171,631

12 Claims. (Cl. 30—43)

This invention relates to razors of the so-called dry type and more particularly to an improvement in the cutting head thereof.

Heretofore the cutting head on razors of this type has been located in line with and at the end of a hand grip containing the motor. With a head of this type it is necessary to hold the entire device at approximately right angles to the face which often results in the hand of the user assuming an uncomfortable and usually awkward position.

It is the aim of this invention to provide a razor the head of which is adjustable thereby permitting the user to set it at the angle most convenient for easy and natural use.

The principal object of this invention is to provide an adjustable cutting head for razors of the dry type which may be rotated to any one of a plurality of positions in angular relation with the grip portion.

Another object of the invention is to provide an improved driving means for the cutting head which will permit angular adjustment thereof.

A still further object of the invention is to provide a dry shaver which may be easily and naturally gripped by the user while shaving.

A more clear conception of the operation, construction and further objects may be had from the following specification taken in conjunction with the accompanying drawings in which:

Fig. 1 is an end elevation of a razor embodying the features of the invention with the cutter head shown substantially at ninety degrees to the grip portion of the device.

Fig. 2 is a rear elevation of the razor with the cutting head in the same position as shown in Fig. 1.

Fig. 3 is an enlarged cross sectional view taken along line 3—3 of Fig. 1 showing the drive mechanism.

Fig. 4 is a cross sectional view taken along line 4—4 of Fig. 3.

Fig. 5 is an enlarged cross sectional view taken along 5—5 of Fig. 2 showing the drive mechanism.

Fig. 6 is a cross sectional view taken along 6—6 of Fig. 5.

Fig. 7 is a front elevation of the head portion of the razor showing the cutting head in alignment with the grip portion of the device.

Fig. 8 is a modified form of the device.

Referring to the drawings in detail, and particularly to Figs. 1 to 7, inclusive, 10 indicates a housing which forms a hand grip and encloses a motor of any suitable well-known type. The

motor is not shown or further described as it forms no part of the present invention. The housing 10 is formed at its upper end with a pair of arcuate supporting elements 11 which are secured together by an arcuate web 12. At the base of the web 12 is a longitudinal stop ledge 13. At the side opposite the ledge 13 is formed a second stop element 14. A motor driven shaft 15 is supported vertically in housing 10 and carries at its upper end a cam or eccentric 16.

A second housing 17 is formed with end elements having their lower extremities arcuate in shape and adapted to straddle the elements 11. This upper housing is pivotally mounted on a rod 18 passing through the ends of housing 17 and the elements 11. The upper housing 17 is formed with a stop 19 to coact with ledge 13 and with a groove 20 to coact with stop 14. The elements 13, 14, 19, and 20, therefore, determine the amount of angular adjustment possible between the housings 10 and 17, which is shown as about 90° although this amount of angular adjustment might be more or less as might be found most suitable. The two housings may be secured in any desired position by tightening a knurled thumb nut 21 on the pivot rod 18.

Mounted freely on rod 18 is a sleeve 22 formed with a groove 23 in its periphery. Into this groove 23 extends the cam or eccentric 16, so that upon each rotation of shaft 15, the sleeve 22 will be given a limited positive reciprocation on rod 18.

Secured in the upper housing 17 is a plate 24 which supports a pair of spring-pressed pins 25, the upper ends of which extend through the housing 17. The springs 26 for these pins 25 are confined between the plate 24 and collars 27 formed on the pins. Pivotal secured to the housing 17 by a shoulder screw 28 is a rock lever 29, the lower arm of which extends through a slot in plate 24 and has its end extended into groove 23 of sleeve 22. The upper end of housing 17 is formed to receive a cutter head and carries a lug 30 for accurately determining the position of the cutter head as is well-known in the art.

The cutter head proper consists essentially of a body portion 31 on which is formed the outer series of cutter teeth or blades, and a reciprocating inner cutter 32. Pins 25 pass through apertures in the body portion 31 and enter depressions in the inner cutter 32 so as to press the cutting surface of the latter into intimate contact with the inner surface of the teeth or blades of the outer cutter. A pin 33 in the body

31 enters a slot in the inner cutter so as to prevent rotary movement of the latter. The upper arm of rock-lever 29 extends through a slot in the body portion 31 and has its end extended into a slot in the inner cutter 32.

Figure 8 represents a modified form of the device described herein and reveals a construction of the razor herein adapted to be angularly adjustable on either side. Both sides appear symmetrical and have similar grooves.

It will now be seen that by loosening the nut 21, the housing 17 may be moved about the rod 18 to any desired angle within the limits defined above, and that in every position, the lower end of rock-lever 29 will be in the peripheral groove 23 of the sleeve 22, so that any movement of sleeve 22 by eccentric 14 will be transmitted to rock lever 29 and by the latter to the inner cutter 32. As the upper housing is moved from the position shown in Fig. 5 to the position shown in Fig. 4 the web or apron 12 will be exposed but forms an effective shield for preventing anything from entering the housing at this point. The front of the housing 17 is formed arcuate to provide such a shield when the adjustment is made from the position shown in Fig. 4 to the position shown in Fig. 5, a small slot being formed at 34 to pass about shaft 15 when the position of Fig. 4 is desired.

It will also be noted that with the stops provided, the device has a firm seat in either of its extreme positions.

While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a device of the class described, the combination of a lower housing, a rotatable shaft supported thereby, a cam on said shaft, an upper housing, a pivot rod adjustably securing the upper housing to the lower housing, a sleeve on said rod and formed with a groove coacting with said cam, a rock lever pivoted in said upper housing and coacting with said sleeve, and a cutter supported by said upper housing and operable by said lever.

2. The combination of a lower housing, an upper housing having shearing members, a transverse rod pivotally connecting both said housings, means on said transverse rod for adjustably securing said housings in any one of a plurality of angular adjustments and additional means slidably mounted on said rod for reciprocating one of said shearing members.

3. The combination of a lower housing, an upper housing having shearing members, a transverse rod pivotally connecting both said housings, a knurled nut on said transverse rod for adjustably securing said housings in a plurality of angular adjustments and means mounted on said rod for reciprocating one of said shearing members.

4. The combination of a lower housing, an upper housing supported on said lower housing by a transverse rod, means on said transverse rod to pivotally secure said upper housing to said lower housing in any one of a plurality of angular adjustments, an outer shearing member, an inner

shearing member mounted therein said shearing members being secured in said upper housing, and means in said lower housing to effect a reciprocal movement of the said inner shearing member with respect to the other.

5. The combination of a lower housing, an upper housing supported on said lower housing by a transverse rod, means on said transverse rod to operably secure said upper housing to said lower housing in any one of a plurality of angular adjustments, an outer shearing member, an inner shearing member mounted therein said shearing members being secured in said upper housing, and means in said lower housing to effect a reciprocal movement of the said inner shearing member with respect to the other.

6. The combination of a lower housing, a rotatable shaft supported thereby, a cam on said shaft, an upper housing, a transverse rod adjustably securing the upper housing to the lower housing, a sleeve on said rod and formed with a groove coacting with said cam, a rock lever pivoted in said upper housing and coacting with said sleeve, a cutter supported by said upper housing and operable by said lever, and means for adjustably securing said housings in any one of a plurality of angular adjustments.

7. The combination of a lower housing, a rotatable shaft supported thereby, a cam on said shaft, an upper housing, a transverse rod adjustably securing the upper housing to the lower housing, a sleeve on said rod and formed, with a groove coacting with said cam, a rock lever pivoted in said upper housing and coacting with said sleeve, a cutter supported by said upper housing and operable by said lever, and means for adjustably securing said housings in any one of a plurality of angular adjustments in which the coactive relation of the parts is maintained.

8. A device of the type described consisting of a lower housing and an upper housing having shearing members therein, a transverse rod having means thereon for reciprocating one of said shearing members and connecting the said housings upon which rod as an axis the upper housing may be rotated with respect to the lower housing to any angular position desired, a knurled thumb piece on one end of said transverse bar securing said upper housing at the angular adjustment desired, and elements on said lower housing to determine the degree of said angular adjustments.

9. A device of the type described consisting of a lower and an upper housing, a transverse rod connecting the said housings upon which rod as an axis the upper housing may be rotated with respect to the lower housing to any angular position desired, a knurled thumb piece on one end of said transverse bar securing said upper housing at the angular adjustment desired, and elements on said lower housing to determine the degree of said angular adjustments, and means to maintain the operable coactiveness of the parts of said device in whatever position the upper housing may be adjustably secured.

10. A device of the type described consisting of a lower and an upper housing, a transverse rod connecting the said housings upon which rod as an axis the upper housing may be rotated with respect to the lower housing to any angular position desired, a knurled thumb piece on one end of said transverse bar operably securing said upper housing at the angular adjustment desired, and elements on said lower housing to determine the degree of said angular adjustments, an outer

cutter and an inner cutter mounted therein said shearing members being secured in said upper housing, and means in said lower housing engaging said inner cutter for imparting to it a reciprocatory movement.

5 11. A device of the type described consisting of a lower and an upper housing, a transverse rod connecting the said housings upon which rod as an axis the upper housing may be rotated with respect to the lower housing to any angular position desired, a knurled thumb piece on one end of said transverse bar operably securing said upper housing at the angular adjustment desired, and elements on said lower housing to determine the degree of said angular adjustments, a rotatable shaft, a cam on said shaft, a sleeve on said transverse rod engaging said cam, a rock lever also coactive with said sleeve, an outer cutter 10 and an inner cutter mounted therein and means

for engaging said inner cutter for imparting to it a reciprocatory movement.

12. A device of the type described consisting of a lower and an upper housing, a transverse rod connecting the said housings upon which rod as an axis the upper housing may be rotated with respect to the lower housing to any angular position desired, a knurled thumb piece on one end of said transverse bar operably securing said upper housing at the angular adjustment desired, 15 and elements on said lower housing to determine the degree of said angular adjustments, a rotatable shaft, a cam on said shaft, a sleeve on said transverse rod engaging said cam, a rock lever coactive with said sleeve, a web to shield parts exposed by the said angular adjustments, an outer cutter and an inner cutter mounted therein and means for engaging said inner cutter for imparting to it a reciprocatory movement.
